UNITED STATES PATENT OFFICE.

FRED C. HOWE, OF PASADENA, CALIFORNIA.

FAN.

Application filed June 15, 1927. Serial No. 199,015.

This invention relates generally to power driven rotary fans, with more particular reference to improvements in the fan shown and described in my prior Patent, No. 5 1,247,888, of November 27, 1917.

The device of my prior patent, like the one shown and described herein, was designed to eliminate the objectionable attributes of a fan which functioned only 10 through its potential capacity to develop a more or less powerful current of air in one general direction—this direction being either constant or continuously deflected by bodily oscillation of the rotating fan blades through 15 a predetermined arc.

This and other objections were largely overcome by the device of my prior patent through the provision of fan blades of such configuration, disposition and movement as 20 to radiate air currents, not only horizontally in all directions but in all directions between the horizontal and the vertical, thereby not only so modifying "the velocity of the air currents as to insure the end desired, 25 without superfluous or objectionably sudden, results," in their effect upon bodies against which they are directed, but also generating "air currents the direction of which is predetermined to conform to the 30 hygienic principles of ventilation and air diffusion."

In practice, however, I have found that the directing of air currents of any appreciable intensity above what may be termed 35 the horizontal plane of the fan is not only unnecessary, but curtails, to a great or less degree, maximum diffusive efficiency. If currents are radiated vertically as well as horizontally, including all directions between the vertical and the horizontal, it 40 will be apparent that current will meet current to produce merely a more or less heterogeneous mulling of the air; whereas, if the currents are radiated horizontally only, when 45 they reach the side walls of the room or chamber they will be deflected upwardly, pursuing the course of least resistance, and in the absence of counteracting currents downwardly deflected from an upwardly directing source, the driven air will be returned to and drawn into the fan for redistribution in the same manner—with the added attribute of such exhaustion and replenishment as would, in the circumstances, 50 be attendant if the chamber were not hermetically sealed.

Therefore, one of the more important objects of the present invention is the elimination, so far as practical and expedient, of the more pronounced upwardly directed air 60 currents energized by the fan of my prior patent, at the same time providing an intake at the top as well as the bottom of the fan, thereby not only intensifying the substantially horizontally directed currents 65 through enhanced air supply, but creating reflex currents into the fan from above and thus establishing continuously homogeneous circulation through regular paths which include the extreme upper air-stratum of the 70 chamber.

Among other objects may be mentioned those of simplicity of construction, ease of operation, maximum efficiency with a minimum of power, and comparatively low cost 75 of production.

My invention will be more readily understood by reference to the accompanying drawings, forming a part of this specification, in which— 80

Fig. 1 is a side elevation of a practical and convenient embodiment of the invention;

Fig. 2 is a similar view, on an enlarged scale, of the fan by itself, without the support, driving mechanism and protecting 85 guard or cage;

Fig. 3 is a side view, on a still further enlarged scale, of one of the fan blades;

Fig. 4 is a fragmentary edge view of the upper portion of the same, and 90

Fig. 5 is a transverse section taken substantially on the line 5—5 of Fig. 4.

Referring now to the drawings in detail, numeral 7 designates the housing of an electric motor of any preferred standard make 95 or construction and which, as it forms no part of the present invention, need not be described in detail here. This motor is designed to be connected in any common and well-known manner with a suitable source 100 of electric energy, and is preferably provided with a base 8 in order that the device as a whole may be stably supported upon a table, desk or the like. The motor shaft 9 projects through the upper face of the housing or casing 7 where I have shown it provided with a tapering or substantially conical block or hub 10 and a reduced extension 11, the latter being capped with a correspondingly shaped block or hub 12. These 110 blocks or hubs 10 and 12 provide supports for the sheet-metal fan blades 13, 13.

There may be any desired number of these fan blades. I prefer to employ four, identical in size and shape and best illustrated in Figs. 3 and 4. The major middle portion 5 of each blade 13 is deflected from a radial disposition in a direction opposite that of its normal rotary movement in order to create a radiating flow of air from behind the blade in accordance with the well-known 10 principles of fan-generated currents. In order to obtain highest efficiency, the angle of deflection is of importance. I have found best results are secured from a 45° deflection.

15 Intermediate the middle portion and each end of the blade 13 this deflection from the radial is reversed, through symmetrical torsional curvature, in order that an adequate supply of air may be drawn into the space 20 between the blades from both above and below the fan proper. In order to insure maximum effect of rotation of the blades, a maximum area of each blade should contribute to the generation of outwardly directed 25 currents. At the same time, this maximum effect cannot be secured in the absence of an intake of air for distribution of corresponding capacity. Consequently, not only is the reversed angle of deflection at the end 30 portions 15, 15 of the blades of importance, but also the location and abruptness of the lateral or torsional curvature at 16.

Referring to Fig. 3 the inner edge of the blade is shown at 15, and the outer edge at 35 14, and the middle portion of the blade is coming towards the observer, said blade being supposed to be arranged on a vertical axis passing through or near the upper and lower ends of the blade. The result of this 40 is that the middle portion of the blade forces air horizontally to the right as viewed in said figure, while the end portions of the blade, being reversely inclined, force the air inwardly along the axis of rotation of the 45 blade.

Of course, as air is withdrawn from the space between the blades for radial ejection, a partial vacuum is created and this 50 pressure variation in itself would naturally result in a constant flow of air into the fan from both above and below the same. However, the withdrawal is continuous, and in the absence of some means for augmenting the natural replenishment the flow of air 55 into the fan would lag behind the discharge therefrom, curtailing the supply for distribution and obviously precluding maximum efficiency. Therefore, I laterally deflect the blade-ends in a direction opposite to that of the middle portion of the blade in order to 60 augment the volume of flow of air into the fan.

However, in view of the assistance rendered by the partial vacuum between the rotating blades, the surface area of the blade 65

which is disposed to augment the natural flow of air into the fan may be materially less than the surface area disposed to create the radial discharge therefrom. In fact, I have found that the reverse deflection at the 70 blade-ends may be of just sufficient surface-area as to permit of symmetrical torsional curvature of the blade through a maximum arc of 90°—for I have also found that if I make this angle of reverse deflection 45° 75 from the radial, as best shown in Figs. 4 and 5, I can give maximum area to the effective portions of the blades, with adequate air supply, and thus secure the most effective functioning of the fan without employing 80 blades of undue or inconvenient size.

The extreme ends 17, 17, of each blade are bent and curved to fit the tapering faces 18 and 19 of the blocks 10 and 12, respectively, where they are firmly secured by screws or 85 rivets 20 or in any other suitable manner. It will be noted that in reversely deflecting the blade-ends from the radial to augment the air supply, I also so dispose these ends as to avoid excessive curvature or bending in providing a configuration which insures snug, 90 firm and dependable attachment to the tapering faces of the blocks 10 and 12.

In Fig. 1 I have shown, partly broken away, a wire guard or cage 21, of substantially spherical form, serving the usual protective purposes without detracting from the generally pleasing appearance of the fan when in or out of use.

The device of my present invention has 100 all of the advantages enumerated with respect to the fan of my prior patent, aforesaid, with the added advantages of greater economy of manufacture and ease of operation, together with enhanced effectiveness 105 size for size.

I claim as my invention:

1. A fan comprising a rotatable element and a plurality of blades mounted thereon to revolve therewith, said blades being disposed longitudinally and substantially edgewise with respect to the axis of revolution, the middle portion of each blade being laterally inclined from the radial in a direction opposite to that of its normal movement, and the end portions of said blade inclined in the reverse direction.

2. In a fan, the combination of a motor having a substantially vertically disposed armature shaft, blades mounted on said shaft to revolve therewith, said blades being disposed longitudinally and substantially edgewise with respect to the axis of revolution and both ends of each thereof being secured to said shaft, the middle portion of each blade being laterally inclined from the radial in a direction opposite to that of its normal movement, and the end portions of each blade being inclined in the reverse direction.

3. A fan comprising a rotatable element and a plurality of blades mounted thereon to revolve therewith, said blades being disposed longitudinally and substantially edge-wise with respect to the axis of revolution, the middle portion of each blade being laterally inclined from the radial at an angle of approximately 45° in a direction opposite to that of its normal movement, and the end portions of each blade being inclined in the reverse direction.

4. A fan comprising a rotatable element and blades mounted thereon to revolve therewith, said blades being disposed longitudinally and substantially edge-wise with respect to the axis of revolution, the middle portion of each blade being laterally inclined from the radial at an angle of approximately 45° in a direction opposite to that of its normal movement, and the end portions of each blade being inclined in the reverse direction at a substantially equivalent angle.

5. A fan comprising a rotatable element and a plurality of blades mounted thereon to revolve therewith, said blades being disposed longitudinally and substantially edge-wise with respect to the axis of revolution and both ends of each blade being secured to said rotatable element, the middle portion of each blade being laterally inclined from the radial at an angle of approximately 45° in a direction opposite to that of its normal

movement, and the end portions of each blade being inclined in the reverse direction at a substantially equivalent angle. 35

6. A semi-circular fan blade having its middle portion inclined so that its inner edge is in advance of its outer edge relative to its direction of movement about an axis, and having its end portions inclined so that the outer edge of the blade is in advance of the inner edge of the blade, when the blade is moved about an axis which is located at the two ends of the blade, whereby the middle portion of said blade propels air away 45 from said axis and both ends of said blade draw the air inward along such axis.

7. A fan comprising a rotatable element and a plurality of semi-circular blades mounted thereon to revolve therewith, each 50 of said blades having its middle portion inclined so that its inner edge is in advance of its outer edge relative to its direction of movement, about the axis of said rotatable element, and having its end portions inclined 55 so that the outer edge of the blade is in advance of the inner edge of the blade, when the blade is moved about said axis, whereby the middle portion of said blade propels air away from said axis and both ends of said 60 blade draw the air inward along such axis.

In testimony whereof I affix my signature.

FRED C. HOWE.
